[57]

ABSTRACT

A set of golf clubs which utilizes progressively longer hosel lengths for the purpose of enlarging the main body of the clubhead and/or redistributing weight within the main body of the clubhead. The hosel length progresses from a very short hosel (1 1/2") on the lowest lofted iron, (the number 1 iron), to a conventional length hosel (2 1/2") on the sand wedge. By reducing the length of the hosel, weight is made available that can be used to enlarge the size of the clubhead and/or redistribute weight within the main body of the clubhead.

FIG. 2

FIG. 3

FIG. 4

FIG. 6

FIG. 7

GOLF CLUB SETS

BACKGROUND OF THE INVENTION

The invention relates to golf clubheads, and in particular, to golf clubheads having varying hosel lengths in order to achieve optimum clubhead size and weight distribution within the main body of the clubhead.

The hosel portion of a golf club is the tubular shaped member which connects the head portion of the club to the shaft portion of the club. Hosels are generally all the same length, i.e., they do not vary from club to club within a set.

Golf club irons are designed with varying degrees of loft, ranging from a minimum of about 15° for a number 1 iron to a maximum of about 60° for a wedge type club. Golf clubs also vary in length. Golf club woods are designed with varying degrees of loft ranging from about 8° to about 27°. The different degrees of loft and length help to control the trajectory and distance a golf ball is hit. With reference to FIG. 1, a golf club iron includes a blade member 2 having a toe portion 4, a top ridge 6, a bottom sole portion 8 and a heel portion 10. Extending from the heel portion region of the clubhead is a hosel portion 12 adapted to receive and be retained on a shaft member (not shown). The clubhead is provided with a substantially flat surface 16, having therein a center of percussion 18, which is the spot ideally adapted to engage a golf ball at impact, and a rear surface 20 having a perimeter 22 defining a cavity 24.

One of the problems associated with the less lofted clubs is that the size of those clubs has generally been restricted by the head weight. The less lofted iron clubheads are typically the lightest weight because they will be cut to the longest overall club length and must still be within an acceptable swing weight range. These restrictions have thus far dictated that the size of the main body of the less lofted iron clubhead remain very small volumetrically. It is desirable to increase the size of the main body of the less lofted clubs in order to make them easier to hit.

It is also desirable to provide more of an impact on the actual distribution of weight within the normal golf clubhead shape or profile. The optimum weight distribution system of an iron type golf clubhead is one in which the optimum amount of weight is positioned toward the toe area of the head on the less lofted clubs and progressively shifts toward the heel area of the head on the more lofted clubs. Placement of the weight in these positions helps eliminate the average golfer's natural tendency to hit the ball to the right when using the less lofted clubs, and hit the ball to the left when using the more lofted clubs. Efforts to move or redistribute enough weight to produce a significant impact in this area have not been completely successful because there is simply not enough material or mass contained within the main body of the conventional clubhead profile which could be moved or redistributed to effectively achieve the optimum results.

One attempt at improvement in this area has been the use of hosels of varying lengths to permit redistribution of weight within the main body of the clubhead. U.S. Pat. No. 4,715,601 to Lamanna discloses the use of hosels of varying lengths to achieve a relatively constant center of percussion for the set of lofted clubs. Lamanna discloses a design for clubs in which the hosel portions of the clubs progress in length as the loft increases, with the standard or conventional length hosel on the lowest

lofted club and the longest, or longer than conventional length hosel on the highest lofted club. As the clubhead weight increases from the lower lofted irons to the higher lofted irons, the weight of the hosel portion also increases. Therefore, the center of mass is maintained at a relatively constant location in relation to the blade portion of the clubhead and the planar face of the blade portion.

Thus, Lamanna discloses that the location of center of mass remains relatively constant for all of the various lofted clubs. As mentioned above, it is desirable to have a set of golf clubs in which the center of mass shifts, with the optimum amount of weight toward the toe area on the less lofted clubs shifting progressively toward the heel on the more lofted club.

SUMMARY OF THE INVENTION

Thus, it is an object of the present invention is to provide a set of golf clubs in which the size of the main body of the less lofted clubs is increased to make them easier to hit.

It is a further object of the present invention to provide a set of golf clubs having more of an impact on the actual distribution of weight within the normal golf clubhead shape or profile.

It is a further object of the present invention to provide a golf clubhead in which the optimum amount of weight is moved toward the toe area of the head on the less lofted clubs with the weight shifting progressively toward the heel area of the head on the more lofted clubs. This locates the center of gravity of each clubhead in an optimum position.

It is a further object of the present invention to provide a golf club which will help eliminate the average golfer's natural tendency to hit the ball to the right when using the less lofted clubs and hit the ball to the left when using the more lofted clubs.

The invention achieves the objectives set forth above by providing a set of golf clubs which utilizes progressively longer hosel lengths for the purpose of enlarging the main body of the clubhead and/or redistributing weight within the main body of the clubhead. The hosel length progresses from a very short hosel (1 1/8") on the lowest lofted iron, (the number 1 iron), to a conventional length hosel (2 1/8") on the sand wedge. By reducing the length of the hosel, weight is made available that can be used to enlarge the size of the clubhead and/or redistribute weight within the main body of the clubhead. Specifically, the overall size of the number 1 iron can be increased to that of a number 3 iron, with the size of the sand wedge remaining standard and all clubs in between progressing in size in order to maintain continuity in the set. The increase in size of the main body of the clubhead makes the club easier to hit.

The extra weight may also be redistributed around the perimeter of the cavity in order to shift the center of gravity to the optimum position to maximize the distance and direction when striking a golf ball. In the less lofted clubs, the weight is redistributed toward the toe area and then moves back progressively toward the heel in the more lofted clubs.

The above and other features of the invention, including various novel details of construction and combination of parts, will now be more particularly described with reference to the accompanying drawings and pointed out in the claims. It will be understood that the particular devices embodying the invention are shown

by way of illustration only and not as limitations of the invention. The principles and features of this invention may be employed in various and numerous embodiments without departing from the scope of the invention.

BRIEF DESCRIPTION OF THE DRAWING

Reference is made to the accompanying drawing in which is shown an illustrative embodiment of the invention from which its novel features and advantages will be apparent.

In the drawing:

FIG. 1 shows an iron golf clubhead;

FIG. 2 shows a back view of set of golf club irons according to the invention;

FIG. 3 shows a front view of a set of golf club irons according to the invention;

FIG. 4 shows a side comparison of the varying hosel lengths according to the invention;

FIG. 5 shows a front view of golf club woods according to the invention;

FIG. 6 shows a blind bore section of a hosel;

FIG. 7 shows a golf club wood having an enlarged face.

DESCRIPTION OF THE PREFERRED EMBODIMENT

Referring to the drawing, and particularly FIGS. 1 and 2, it will be seen that the illustrative golf clubhead includes a blade member 2 having a toe portion 4, a top ridge portion 6, a bottom sole portion 8 and a heel portion 10. Extending from the heel portion region of the clubhead is a hosel portion 12 adapted to receive and be retained on a shaft member (not shown). The clubhead is provided with a substantially flat surface 16, having therein a center of percussion 18, which is the spot ideally adapted to engage a golf ball at impact, and a rear surface 20 having a perimeter 22 defining a cavity 24.

FIGS. 2-4 show a set of clubs including irons numbers 1-9 and the pitching wedge and sand wedge. The hosel length of the number 1 iron is reduced from the standard length of $2\frac{1}{8}$ " to $1\frac{1}{8}$ ", and the length of each hosel progresses $\frac{1}{8}$ " per club to a conventional $2\frac{1}{8}$ " length on the sand wedge. FIG. 4 shows a side view 45 comparison of the hosel lengths for each iron. The hosel offsets progress from 0.276" on the number 1 iron to 0.076" on the sand wedge, thereby giving the appearance of a straight or conventional blade on the short irons.

The leading edge 30 of the clubhead is straight or without toe to heel radius. The leading edge 30 may be radiused or rolled in the direction from the bottom of the face to the sole. There is no indentation where the leading edge blends into the hosel from the number 8 55 iron through the sand wedge.

In a first embodiment, the weight made available from reducing the size of the hosel 12 is used to enlarge the size of the clubhead. For example, the overall size of the number 1 iron is increased to that of a conventional number 3 iron. The overall size of the sand wedge remains conventional and all clubs in between progress in size in order to maintain continuity in the set.

By reducing the length of the number 1 iron hosel from its normal length of $2\frac{1}{8}$ to approximately $1\frac{1}{8}$, approximately 35 grams of weight are removed which may be used to increase the size of the main body. As an example, in a typical set of golf club irons, the head

weight specification increases 7 grams per club number, i.e. a normal number 1 iron head weight specification is 232 grams, the number 2 iron head weight is 239 grams, etc. By reducing the hosel length on the number 1 iron 5 and utilizing a very thin ($\frac{1}{8}$ ") blind bore hosel configuration, as shown in FIG. 6, approximately 35 grams of weight can be redistributed over the main body of the clubhead. That excess weight makes it possible to produce a number 1 iron with a main body size which is volumetrically similar to that of a conventional number 3 iron. Once the main body of the iron is increased to the size of a number 3 iron, the sand wedge remains at a standard size and all club members in between are progressive.

15 FIG. 6 shows a blind bore section of a hosel. The oval 44 represents the angle cut inside the bore. The dotted lines 46 represent the hosel bore and the area 42 between the oval 44 and the sole 8 is the blind bore section.

20 As the hosel length increases by $\frac{1}{8}$ " per club number, the blind bore section located at the base of the hosel will also increase or get thicker by an additional $\frac{1}{8}$ " per club number, or in other words, the hosel bore depth remains constant at $1\frac{1}{8}$ " throughout the set for the number 1 iron through the sand wedge due to the progressively increasing blind bore section. In order to accomplish this, the tips of the shafts used on the short hosel clubs, i.e. the numbers 1 through 4 irons, are cut at exact matching angles to fit properly. This procedure also creates a mechanical locking device thus improving the aspect of clubhead to shaft bonding.

25 The invention is applicable to woods as well as irons because the same features are desired on both, i.e. maximum enlargement of the main body of the less lofted clubs. FIG. 5 shows a front view of the varying hosel lengths for the driver and numbers 1, 3, 5 and 7 woods.

30 The physical dimensions of the progressive length hosel theory of the main body head enlargement are outlined below:

Club No.	Approx. Overall Hosel Length	Approx. Hosel Bore Depth	Approximate Hosel Bore Configuration	
			WOODS	IRONS
1	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
3	$2\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
5	$2\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
7	$3\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
1	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
2	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
3	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
4	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
5	$1\frac{1}{8}$ "	$1\frac{1}{8}$ "	Blind bore with shaft stopping $\frac{1}{8}$ " from sole of club	Blind bore with $\frac{1}{8}$ " solid section between bottom of hosel and sole of club
6	2"	$1\frac{1}{8}$ "	Blind bore with shaft stopping $\frac{1}{8}$ " from sole of club	Blind bore with $\frac{1}{8}$ " solid section between bottom of hosel and sole of club

-continued

Club No.	Approx. Overall Hosel Length	Approx. Hosel Bore Depth	Approximate Hosel Bore Configuration
7	24"	14"	Blind bore with 1" solid section between bottom of hosel and sole of club
8	24"	14"	Blind bore with 1" solid section between bottom of hosel and sole of club
9	24"	14"	Blind bore with 14" solid section between bottom of hosel and sole of club
PW	24"	14"	Blind bore with 14" solid section between bottom of hosel and sole of club
SW	24"	14"	Blind bore with 14" solid section between bottom of hosel and sole of club

In a second embodiment, the weight available from reducing the hosel length on the less lofted clubs is used to redistribute the weight within the main body of the 25 clubhead. As mentioned above, by reducing the hosel length to approximately 14" long and utilizing a very thin 1" blind bore type hosel configuration, approximately 35 grams of weight can be removed from the heel section of the clubhead which can then be redistributed to the toe area of the head, thus greatly impacting the center of percussion or weight distribution of the head. The 35 grams of mass is moved to the toe area of the number 1 iron. The mass can be gradually moved back toward the heel area of the clubhead by increasing the length of the hosel by 1" per club until the conventional 24" overall hosel length is achieved on the sand wedge.

The weight which is removed from the hosel area may be redistributed around the perimeter of the cavity. Weight may be positioned low in the sole and toward the toe on the less lofted irons and progress toward the heel on the more lofted irons. This dramatically increases the toe/heel weighting aspect within the main body of the clubhead.

As the hosel length increases by 1" per club number, the blind bore section at the base of the hosel will also 50 increase or get thicker by an additional 1" per club number, or in other words, the hosel bore depth would remain constant at 14" throughout the set from the number 1 iron through the sand wedge due to the progressively increasing blind bore section. In order to accomplish this, the tips of the shafts used on the short hosel clubs, i.e. the number 1 iron through the number 4 iron, are cut to an exact matching angle for proper fit. This procedure also creates a mechanical locking device thus improving the aspect of clubhead to shaft bonding.

This theory is also applicable to woods as well as irons because the same distribution of weight features are desired on both, i.e. the optimum amount of weight located toward the toe on the less lofted clubs (i.e. the driver and the number 1 iron) progressively moved

toward the heel on the more lofted clubs (number 7 wood and sand wedge).

As an alternative, a wood clubhead with a conventionally sized main body can be improved by redistributing weight from the hosel 12 to the face area 32. By extending the face height, an enlarged hitting surface is created utilizing a high lip 34 across the topline of the face 38, as shown in FIG. 7. This face extension or lip 34 is highest on the less lofted clubs (or driver) progressively decreasing in size on the more lofted clubs (or 7 wood).

The physical dimensions of the progressive length hosel theory of weight distribution are outlined below:

15

Club No.	Approx. Overall Hosel Length	Approx. Hosel Bore Depth	Approximate Hosel Bore Configuration
WOODS			
1	14"	14"	Blind bore with shaft stopping 1" from sole of club
3	24"	14"	Blind bore with shaft stopping 1" from sole of club
5	24"	14"	Blind bore with shaft stopping 1" from sole of club
7	34"	14"	Blind bore with shaft stopping 1" from sole of club
IRONS			
1	14"	14"	Blind bore with 1" solid section between bottom of hosel and sole of club
2	14"	14"	Blind bore with 1" solid section between bottom of hosel and sole of club
3	14"	14"	Blind bore with 1" solid section between bottom of hosel and sole of club
4	14"	14"	Blind bore with 1" solid section between bottom of hosel and sole of club
5	14"	14"	Blind bore with 1" solid section between bottom of hosel and sole of club
6	2"	14"	Blind bore with 1" solid section between bottom of hosel and sole of club
7	24"	14"	Blind bore with 1" solid section between bottom of hosel and sole of club
8	24"	14"	Blind bore with 1" solid section between bottom of hosel and sole of club
9	24"	14"	Blind bore with 14" solid section between bottom of hosel and sole of club
PW	24"	14"	Blind bore with 14" solid section between bottom of hosel and sole of club
SW	24"	14"	Blind bore with 14" solid section between bottom of hosel and sole of club

In a third embodiment, the weight made from reducing the length of the hosel is used both to increase the size of the clubheads and to shift the weight toward the toe on the less lofted clubs and toward the heel on the highest lofted clubs. The physical dimensions of the clubheads embodying those features are outlined below:

65

approximately 1 $\frac{1}{2}$ " for the least lofted club to approximately 3 $\frac{1}{8}$ " for the highest lofted club.

12. The set of golf club woods of claim 10 wherein the weight of the head portion of the least lofted club is between 195 g and 198 g and the weight of the head portion of the highest lofted club is between 214 g and 220 g.

13. The set of golf club woods of claim 10 wherein each club has a blind bore with a shaft stop at a base of

the hosel and the thickness of the blind bore of the least lofted club is approximately $\frac{1}{8}$ ".

14. The set of golf club woods of claim 10 further comprising a face, and a face extension extending at least as high as a highest point on the head portion, with the face extension highest on the least lofted club and progressively decreasing in size as the loft increases.

15. The set of golf clubs of claim 10 wherein the head weight of the club of the least lofted club is approximately 195 g and the weight of each club in the set increases progressively as the club increases in loft.
